UNITED STATES PATENT OFFICE.

ALBERT G. SPALDING, OF POINT LOMA, CALIFORNIA.

DESIGN FOR A TROPHY.

40,930.

Specification for Design.

Patented Oct. 4, 1910.

Application filed July 16, 1910. Serial No. 572,389. Term of patent 14 years.

To all whom it may concern:

Be it known that I, ALBERT G. SPALDING, a citizen of the United States, residing at Point Loma, San Diego county, and State of California, have invented a new, original, and ornamental Design for a Trophy, of which the following is a specification.

The nature of my design is fully represented in the accompanying drawing, to

which reference is made and which shows in perspective, a trophy embodying my design.

I claim,

The ornamental design for a trophy, as shown.

ALBERT G. SPALDING.
